(57) **CLAIM**

The ornamental design for a waterproof phone case, as shown and described.

DESCRIPTION

FIG. 1 is a front and left-side perspective view of a waterproof phone case showing a first embodiment of my new design;

FIG. 2 is a rear, right-side, and bottom perspective view thereof;

FIG. 3 is a front view thereof;

FIG. 4 is a rear view thereof;

FIG. 5 is a left-side view thereof;

FIG. 6 is a right-side view thereof;

FIG. 7 is a top view thereof;

FIG. 8 is a bottom view thereof;

FIG. 9 is a front, right-side, and bottom perspective view of a waterproof phone case showing a second embodiment of my new design;

FIG. 10 is a rear and right-side perspective view thereof;

FIG. 11 is a front view thereof;

FIG. 12 is a rear view thereof;

FIG. 13 is a left-side view thereof;

FIG. 14 is a right-side view thereof;

FIG. 15 is a top view thereof;

FIG. 16 is a bottom view thereof;

FIG. 17 is an enlarged detail view of area 17 in FIG. 1;

FIG. 18 is an enlarged detail view of area 18 in FIG. 1;

FIG. 19 is an enlarged detail view of area 19 in FIG. 1; and,

FIG. 20 is an enlarged detail view of area 20 in FIG. 10.

The broken line circles in FIGS. 1, 10, and 17-20 and the curved broken lead lines in FIGS. 1 and 10 form no part of the claimed design; they delineate and indicate portions of the waterproof phone case, including claimed subject matter, that are shown on an enlarged scale in FIGS. 17-20. All other broken lines throughout the drawing figures form no part of the claimed design, and they depict portions of the waterproof phone case that form no part of the claimed design.

1 Claim, 20 Drawing Sheets
